BUCKET

George Yates, Jr., Glendale, Calif., assignor to Bennett Industries, Inc., Peotone, Ill., a corporation of Delaware

Filed Sept. 27, 1968, Ser. No. 13,761

Term of patent 14 years

Int. Cl. D7—06

U.S. Cl. D49—29

FIGURE 1 is a side elevational view of the bucket showing my new design.

FIGURE 2 is a front elevational view.

FIGURE 3 is a vertical sectional view.

FIGURE 4 is a plan view.

The bottom of the bucket is recessed and has a concentric downwardly projecting flange equal in diameter to the distance between sections of the flange shown in FIGURE 3.

I claim:

The ornamental design for a bucket, as shown and described.
